(57) **CLAIM**

The ornamental design for a faucet body, as shown and described.

DESCRIPTION

FIG. 1 is a front elevational view of a faucet body showing my new design;

FIG. 2 is a rear elevational view thereof;

FIG. 3 is a left side view thereof;

FIG. 4 is a right side view thereof;

FIG. 5 is a top view thereof; and,

FIG. 6 is a bottom view thereof.

Any shading and cross-hatching are not features of the design but are utilized to illustrate the surface contours of the faucet body in the drawings.

The broken lines are included for the purpose of illustrating environmental structure and form no part of the claimed design.
